UNITED STATES PATENT OFFICE

FRANK POWER, OF HORTON, KANSAS

ATTACHMENT FOR AUTOMOBILE RADIATORS

Application filed October 19, 1928. Serial No. 313,541.

My invention relates to improvements in attachments for automobile radiators, and it consists in the combinations, constructions, and arrangements herein described and 5 claimed.

An object of my invention is to provide an attachment for automobile radiators which has a novel means for holding and displaying an advertisement.

10 A further object of my invention is to provide a device of the type described which has a novel means for correctly positioning the device when not in motion.

15 A further object of my invention is to provide a device of the type described which is simple in construction, durable, and efficient for the purpose intended.

20 Other objects and advantages will appear in the following specification, and the novel features of the invention will be particularly pointed out in the appended claims.

My invention is illustrated in the accompanying drawings, forming part of this application, in which

25 Figure 1 is a front elevation of my device as applied to an automobile,

Figure 2 is a top plan view of my device as applied to an automobile, and

30 Figure 3 is a section substantially along the line 3—3 of Figure 1.

In carrying out my invention, I provide a frame 1 which may be of any desired shape, size, or construction. In the present instance the frame 1 is rectangular in general 35 formation and is provided with side walls 2 and 3, and end walls 4 and 5. The end wall 5 is provided with a slot 6 for receiving an advertising card 7. The walls 2, 3, and 4 are provided with grooves 8 for receiving the 40 edges of the advertising card 7. A weight 9 is carried by the wall 4 for a purpose hereinafter described.

A shaft 10 extends through the side walls 2 and 3 of the frame 1. The frame is rotatably mounted upon the shaft 10 and may 45 be operatively connected thereto by means of bearings, as indicated at 11. An arm 12 extends substantially at right angles with respect to the shaft 10 and is provided with 50 a clamp 13 at the free end thereof which is

arranged to be rigidly secured to a radiator 14 of an automobile by any suitable means, such as a bolt 15.

In Figure 2 the frame 1 is shown in close proximity to the radiator, but it will be readily understood that the arm 12 is of sufficient length to permit the frame to rotate.

From the foregoing description of the various parts of the device, the operation thereof may be readily understood. The weight 9 provides a variance in the actual weight of the ends of the frame 1 upon each side of the shaft 10. It will therefore be observed that the end wall 4 will be carried on to the lowermost position and retained in this position while the frame is not in rotatable movement. When any plane-surfaced member, such as the card 7, is balanced and so rotatably mounted that its axis of rotation is at right angles to the movement of the plane-surfaced member through the air, the plane surface of the member will maintain itself in equilibrium at right angles to the air resistance, or in other words, the member will flatten itself against the air. In order to cause the member to rotate, this equilibrium must be overcome. In this device the weights 9 are the means for overcoming the equilibrium. When the automobile starts to move, the device begins swaying, and as the speed of the automobile increases, the air resistance increases the swaying motion until complete rotation is finally established. The rotation of the frame attracts attention to the advertisement contained therein. Furthermore, when the automobile ceases its motion, the advertisement is held in a stationary, upright position.

I claim:

1. A device of the type described comprising a frame having openings therein, bearing members disposed in said openings, a horizontal shaft extending through said bearing members for rotatably supporting said frame, and a bracket carried by said shaft for securing said shaft to a suitable support.

2. A device of the type described comprising a frame having openings therein, bearing members disposed in said openings, a

horizontal shaft extending through said bearing members for rotatably supporting said frame, and a bracket carried by said shaft for securing said shaft to a suitable support, said frame having walls provided with concave portions for receiving a display card.

3. A device of the type described comprising a frame having openings therein, bearing members disposed in said openings, a horizontal shaft extending through said bearing members for rotatably supporting said frame, a bracket carried by said shaft for securing said shaft to a suitable support, said frame having walls provided with concave portions for receiving a display card, and weight members disposed in said frame for unbalancing the ends of said frame whereby said frame may be normally held in a predetermined position.

4. A device of the type described comprising a supporting member attachable to a vehicle and having a bearing portion positioned at right angles to the direction of movement of the vehicle, a sheet rotatably mounted at a mid-point between its ends upon said bearing portion, and a weight connected with one end of said sheet whereby the latter will be rotated whenever the vehicle is moved.

5. A device of the type described comprising a supporting member attachable to a vehicle and having a bearing portion positioned at right angles to the direction of movement of the vehicle, a sheet rotatably mounted at a mid-point between its ends upon said bearing portion, means for operatively connecting the sheet with said bearing portion, and a weight connected with one end of said sheet whereby the latter will be rotated whenever the vehicle is moved.

Signed at Horton, in the county of Brown and State of Kansas, this 8th day of October, A. D. 1928.

FRANK POWER.
